UNITED STATES PATENT OFFICE.

WILLIAM H. DOBLE, OF QUINCY, MASSACHUSETTS, ASSIGNOR TO PNEUMATIC SCALE CORPORATION, LIMITED, OF QUINCY, MASSACHUSETTS, A CORPORATION OF MAINE.

APPARATUS FOR WATERPROOFING FILLED AND SEALED PACKAGES.

1,199,532.

Specification of Letters Patent. Patented Sept. 26, 1916.

Application filed December 21, 1915. Serial No. 67,988.

To all whom it may concern:

Be it known that I, WILLIAM H. DOBLE, a citizen of the United States, residing at Quincy, county of Norfolk, State of Massachusetts, have invented a certain new and useful Improvement in Apparatus for Waterproofing Filled and Sealed Packages, of which the following is a specification, reference being had therein to the accompanying drawings.

It is very important for a variety of reasons both sanitary and preservative that food products put up in packages for the market shall be hermetically sealed and waterproofed. Sometimes this has been attempted by making the carton or package out of material which has been previously waterproofed, sometimes by waterproofing the carton after it has been formed but before it is filled and then sealing the carton after it is filled, and sometimes the filled package which is itself unwaterproofed is wrapped in a waterproofed wrapper. None of these methods makes a waterproof joint. The object of the present invention is to take a filled package which is made of ordinary unwaterproofed material, such, for instance, as paper of which cartons are ordinarily made, seal the filled package in any suitable way, and then to waterproof the filled and sealed package by the exterior surface application of waterproofing preparation thereto.

In the preferred method of carrying out the invention, the waterproofing material consists of paraffin or wax, and the filled and sealed package is immersed in the paraffin while the latter is in a hot liquid state so as to thoroughly cover all parts of the package with a coating of the melted wax, then the package is carried directly into a hot chamber in which it remains long enough for the surplus paraffin to drip off of the package before the paraffin solidifies, and then the package is removed and the film of paraffin which remains upon the package is allowed to harden. This leaves the package in a waterproof and hermetically sealed condition ready for market. It may or may not be inclosed in a wrapper as desired for shipping purposes.

Although the preferred waterproofing material is paraffin, any suitable waterproofing

substance may be employed which can be applied in liquid form and which solidifies when exposed to the atmosphere.

The drawings illustrate one form of apparatus embodying means for carrying out the invention in which the entire process is performed mechanically. It is to be understood however, that the invention is a broad one, and it is not intended to be limited to the particular apparatus shown.

The invention will be fully understood when taken in connection with the accompanying drawings and the novel features thereof will be pointed out and clearly defined in the claims at the close of this specification.

In the drawings, Figure 1 is a side elevation of the apparatus, partly broken away, embodying the invention. Fig. 2 is an elevation looking in the direction of the arrow in Fig. 1. Fig. 3 is a vertical longitudinal section of the apparatus shown in Fig. 1. Fig. 4 is a section on line 4—4 of Fig. 3. Fig. 5 is a detail view showing the gearing for producing the intermittent movement.

Referring now to the drawings, 1 represents a tank which contains the waterproofing material the level of which is represented in the drawings by the dotted line 2. The said tank is shown as mounted upon a platform 3 supported on the upper end of a standard 4 which is vertically movable for the purpose of raising and lowering the tank. The said standard 4 has the lower portion formed as a rack bar with teeth 5 which engage with the teeth of a pinion 6 mounted on a shaft 7 so that by rotating said shaft 7 the said rack bar and standard 4 may be moved up and down to raise and lower the tank 1. The shaft 7 may be rotated by means of a hand wheel 8 mounted on the shaft and will be retained in its adjusted position by means of a pawl 9 which engages with ratchet teeth on a wheel 10, said pawl 9 being pivoted to a stationary part of the frame. A rotary spider 11 is mounted on a shaft 12, said shaft being journaled in bearings 13—14 carried by or formed as a part of I beams 15—16 which form a part of the frame. Said spider 11 is in the form of a circular disk having a plurality of U-shaped notches 17 in its periphery, said notches being disposed at regular intervals

apart from each other. As shown in the drawings said notches are four in number. Attached to the disk, in each one of these U-shaped recesses, is a package holder 18 which is U-shaped in cross section, being open at the top and on each end. These holders are shown as secured to the disk by means of screws 19 which pass through ears 20 and through the disk or spider. The package 5 holders or carriers 18 are of just the right width to hold one of the packages 21 and preferably should be of a little less depth than the length of the package so that when the package is in the holder it will project 10 slightly from the left hand or outer end of the holder as viewed in Fig. 3 for the purpose to be hereinafter described. The shaft 12 on which the spider is mounted stands at an inclination as plainly shown in Fig. 3 15 so that the spider revolves in an inclined plane and the holders 18 which extend at right angles to the plane of the spider are also always at an inclination.

The tank 1 is so located with relation to 20 the spider that during the rotation of the spider each holder 18 will be caused to sweep down through the liquid in the tank. Means are provided by which the spider is given an intermittent movement, rotating at each 25 period of movement through an arc equal to the distance between two of the holders 18. In the form of construction shown in the drawings in which there are four holders at equal distances apart each holder will rotate through an arc of 90° at each period of 30 movement. The arrangement and construction are such that the period of dwell of the disk will occur at the time when the lowermost holder 18 is immersed in the liquid in the tank as shown in dotted lines 35 in Fig. 3. This dwell gives opportunity for the package to become thoroughly covered with the melted paraffin. The dwell also gives opportunity for introducing another 40 package into the holder which follows next behind the one which is already immersed, and for the discharge of the package at the discharge station.

Means are provided whereby the packages 45 may be automatically fed into the holders, one package to each holder in turn as it reaches the station the last before it moves into the bath in the tank. The means provided are as follows: A table 22 having a 50 flange 23 is adjustably secured to the frame 24, as, for instance, by bolts 26 passing through elongated slots 27 in the flange 23 and into the frame. The table should be so adjusted that the top will be in the same 55 plane as the upper surface of the bottom of the holder 18. Two guides 28—28 are secured to the top of the table parallel with each other and spaced apart equal to the 60 width of the package so that there is just room for the package to slide between the 65

guides. The table and guides are so located that the passage between the guides is in alinement with the entrance to the holder 18 at the time when the holder 18 is at the station of rest last before it moves to enter 70 the tank. The attendant will keep the table 22 supplied with packages so that there is always a package ready to enter the holder 18 at the proper time. As the holder 18 is open at the entrance end, and the table 22 75 is at an inclination, the package will slide down into the holder by gravity at the proper time aided by the pressure of the packages behind it. The advance package on the table is held back during the rotation 80 of the spider by reason of the end package engaging with the flat face of the spider, and it is ready to enter the holder as soon as the open space at the end of the holder comes into alinement with the way between 85 the guides 28 on the table.

The reason for having the holder of 90 slightly less depth than the length of the package is so that the package will protrude slightly from the holder and thereby hold 95 back the next following package enough to prevent said next following package from sliding down far enough to catch on the edge of the holder when the spider starts to move again. As soon as the spider moves 95 far enough to cause the contained package to move clear of the next following package in the run way, said following package will slide down into contact with the flat side of the spider ready to slide into the next 100 holder in turn.

It is desirable to have the holder 18 open 105 also at the end opposite the entrance end in order to enable the package to be discharged at the proper time as will be hereinafter described.

On account of the inclined seat for the package in the holder it is necessary to provide means for preventing the package from 110 sliding out of the exit end until the spider 115 in its rotation brings the holder around to the proper station for discharging the package. For this purpose a stop bar 29 bent into hoop shape is provided, one end of which is secured at 30 to a flange 31 forming a part of the frame of the machine, said point of attachment being at a slightly higher elevation than that side of the holder 18 which is on the upper side when the holder is at the station where the package is 120 received, as shown in Fig. 2. Said hoop is concentric with the spider but of less diameter and extends down along side of the exit end of the holder 18 at the package receiving station just in the rear of the exit 125 end. It continues along just in the rear of the path described by the exit end of the holder until it reaches a point just below the station where the package is to be discharged. That end of the hoop is secured 130

to the delivery shelf 32. The hoop thus serves as a stop to prevent the package from sliding out of the end of the holder both at the receiving station and during all of the 5 travel until the package arrives at the discharging station.

The holder 18 is left open at the two ends not only for the purpose of conveniently receiving and discharging the package but 10 also to readily permit contact of the melted paraffin with the package when it is immersed in the bath. For this purpose the top of the holder is also left open but as the holder is in an inverted position when it is 15 in the bath and is also in a somewhat inverted position during a large part of the travel from the receiving station to the discharging station it is necessary to provide means to prevent the package from falling 20 out of the holder. The means provided for this purpose are as follows: A plurality of narrow hoop shaped bars 33 are provided, being shown in the drawings as three in number, each concentric with the path of 25 travel of the holder, and they lie just outside of the periphery of the spider, one end of each of said hoops 33 being secured to a bar 34 connected with the frame, the other ends of said hoops being secured at 35 to 30 the bar 36 at a slightly higher elevation than the upper side of the holder when it is at the discharge station so that the package will be guarded against falling out of the open face of the holder, that is, on the radi ally outward side, at any time after the 35 package has been received in the holder. In order to properly space apart said hoops from each other mid-way of their ends, a bolt 37 passes through a bracket hanger 38 40 and through apertures in the said hoops. Tubular washers 39 are mounted on said bolt between the hoops and between the hanger 38 and the adjacent hoop so that said tubular washers will serve as spacers. Said 45 bolt 37 has a head on the end adjacent the bracket 38 and a nut on the other end to keep it from endwise movement.

The spider 11 is given an intermittent movement already mentioned, moving at 50 each period through an arc equal to the distance between any two of the holders, which in the case of the apparatus shown, is 90°. The means for producing this intermittent movement is as follows: Mounted on a shaft 55 12 is a mutilated or intermittent gear 40 formed with four interruptions or open spaces 41 at an equal distance apart from each other in which there are no teeth. A pinion 42 mounted on shaft 43 engages with 60 said gear 40 and is provided with a single interrupted space 44. The said pinion 42 is of smaller diameter than the gear 40 and is so proportioned thereto that the number of teeth on the pinion 42 is equal to the number of teeth between two of the interruptions 65

on the gear 40, and so arranged that at each rotation of the pinion 42 the interrupted space in the periphery of the pinion 42 will come against one of the interruptions 41 in the periphery of the gear 70 40. It is thus shown in Fig. 2. The pinion 42 is rotating constantly, and at each rotation of said pinion, as long as the teeth of the pinion are engaged with the teeth of the gear 40, said gear 40 will be rotated, 75 thus giving it a quarter turn until the open space 44 in the pinion reaches one of the open spaces 41 in the gear, then the gear 40 will stop rotating until the open space in the pinion shall have rotated past the 80 open space in the gear, and as soon as the teeth of the pinion again engage with the teeth of the gear the gear 40 will be moved again and continue through a one-fourth turn as before. There will thus be a dwell 85 of the spider 11 after each one-fourth turn of the spider for an interval of time sufficient for the teeth of the pinion to again engage with the teeth of the gear. This interval of time will be sufficient for the discharge of the waterproofing package at one 90 end, and for the reception of a new package at the receiving end.

The pinion 42 may be continuously rotated by any suitable mechanism, that shown being 95 as follows: A driving pulley 45 is mounted on a shaft 46 which is journaled in bearings 47, 47 supported by brackets which project from the I beam 16; also mounted on said shaft 46 is a bevel gear 48 which engages 100 with a bevel gear 49 on the shaft 43. Said shaft 43 is mounted in bearings 50 which project from the I beam 16. It will thus be seen that by means of the driving pulley 45, which is continuously driven, and by the 105 connecting mechanism, the pinion 42 is continuously driven and the gear 40 and spider are given the intermittent movement previously described.

It is important that the paraffin in the 110 tank 1 shall be kept hot. Any suitable heating means may be used, that shown being as follows: A gas pipe 51 extends lengthwise beneath the tank near one side, and connected therewith are a plurality of 115 pipes 52 which extend parallel with each other transversely beneath the tank, said pipes 52 being formed with burner apertures 53 so that the said pipes 52 serve as burners to heat the bottom of the tank. The pipe 51 is supplied through a pipe 54 120 which is connected with a flexible section 55 to allow for the raising and lowering of the paraffin tank by means of the pinion 6, and rack 5, in the manner already described. It 125 is intended that the tank shall be lowered when the machine is not in operation so that the spider and holders will be out of the tank, otherwise, when the heat is shut off and the paraffin cools the paraffin will 130

solidify around the submerged holder. In order to prevent undue waste of heat, a hood 56 is provided.

At each period of rest of the spider in its 5 rotation the package which has last come from the paraffin bath is discharged from the spider. The stop hoop 29, as already described, terminates just below the station at 19 which the package stops first after leaving the bath so that the exit end of the holder 18 will be open, thereby leaving a free outlet 15 for the package. On account of the bottom of the holder on which the package is seated being inclined the package will slide out by gravity at the discharge station in the same manner that the package slides in at the receiving station.

The package which has just come from the bath will be so thoroughly drenched with 20 the liquid paraffin that there will be a surplus and it is important that this surplus should be removed before the paraffin hardens. It is preferable to accomplish this removal by natural drainage rather than by 25 positive treatment, like scraping, as drainage leaves a more uniform skin coat, while scraping is liable to remove it unevenly. For this purpose the package is transferred from the spider directly to a drainer where 30 the package is allowed to remain in a heated atmosphere at a sufficiently high temperature to retain the paraffin in its liquid state long enough for all of the surplus liquid to drip from the package. In order to enable 35 the drainage to take place without delay the drainer employed is a carrier of skeleton form which carries the package through a hot chamber so that the drainage can take place while the package is being carried 40 away and the carrier is of sufficient capacity so that additional packages may be deposited successively upon the carrier before the first package is discharged therefrom.

The combination carrier and drainer, as 45 shown, consists of two parallel sprocket chains 57, which run over two pairs of sprocket wheels, 58—59, the pair of sprocket wheels 58 being mounted on a shaft 60 and the pair of sprocket wheels 59 being mounted 50 on a shaft 61. The shaft 60 is located at a somewhat lower level than the exit end of the holder 18 when said holder is at the discharge station, and an inclined slideway 32 which is secured to the frame just below the 55 exit end of the said holder 18 at said discharge station, leads to the carrier chains 57. When a package 21 slides out of the holder 18 it falls on the said slideway 32 and thence slides onto the carrier chains 57. 60 as shown in Fig. 3, in which one of the packages is shown partly on the slideway and partly on the carrier chain. The carrier chains 57 are spaced apart from each other somewhat less than the width of the package 65 so that the package will be supported by

both carrier chains. Underneath the upper run of each of the chains 57 is a rail 63 to prevent the chain from sagging under the weight of the package. The carrier chains 57 pass through a hot chamber which is 70 open at both ends, one end being connected with the hood 56. It is formed as shown with an arched top portion 64, preferably of metal, and a base portion 65. The base is supported on ribs or flanges 66 which form 75 a part of the frame work. Below the lower run of the carrier chain is a drip pan 67 into which the drippings from the packages on the carrier will fall.

Any suitable means may be employed for 80 heating the interior of the chamber 64, the means shown consisting of two parallel gas pipes 68 which extend lengthwise beneath the drip pan 67 above the bottom 65 of said chamber, said pipes 68 having burner apertures 69 therein so as to supply a series of 85 gas jets within the chamber. Said burner pipes 68 are supplied through a pipe 70 which may be the same pipe that supplies gas to heat the paraffin tank. 90

The carrier chains 57 may be driven by any proper connection with the shaft 46 which is driven by the pulley 45, the said driving connection shown being as follows: Mounted on the shaft 60 which carries the 95 sprocket wheels 58 is a sprocket wheel 71, said shaft 60 being mounted in bearings 72 connected with the frame. A sprocket chain 73 runs over said sprocket wheel 71 and over a sprocket wheel 74 mounted on shaft 100 46. The relative size of the sprocket wheels is such as to give the carrier chain 57 whatever speed is desired in relation to the driving shaft 46. The carrier chains may be driven sufficiently slowly to give ample time 105 for the packages to thoroughly drain while being carried through the hot chamber 64. At the outer end of the upper run of the carrier chains the packages will be delivered onto a table 75 whence they may be removed 110 in any suitable way. The package will retain sufficient coating of paraffin after it has passed through the hot chamber 64 to form a waterproof coating over the entire surface of the package. 115

In describing the above apparatus it has been necessary to describe to some extent the waterproofed package and the process for waterproofing the same. The waterproofed package and the process are to form 120 the subjects of separate applications by me.

What I claim is:

1. In an apparatus for waterproofing filled packages, a container which holds a waterproofing substance, and a rotary 125 spider which rotates on an axis inclined to a horizontal, said spider rotating in a plane at right angles to said axis and inclined to a vertical plane, said spider being provided with a plurality of package holders which 130

project therefrom at right angles to the plane of rotation of the spider and are open at each end, and have an inclined seat for the package.

- 5 2. In an apparatus for waterproofing filled packages, a container which holds a waterproofing substance, a rotary carrier which rotates on an axis inclined to a horizontal, said carrier rotating in a plane at 10 right angles to said axis and inclined to a vertical plane, said carrier being provided with a plurality of package holders which project therefrom at right angles to the plane of rotation of the carrier and are open 15 at each end and have an inclined seat for the package, means for rotating said carrier intermittently, an inclined slideway to feed the packages to the holder and which is in alinement with the entrance end of said 20 holder at one of the stations of rest, the waterproof container being so located that the carrier after receiving a package will carry it into and out of said container, a discharge station on the opposite side of the 25 carrier from the loading station and onto which the package will slide out of the holder after the package has been carried through the waterproofing material, and means for preventing the package from sliding 30 out of the holder from the time it is received in the holder until it reaches the discharge station.
3. In an apparatus for waterproofing filled packages, a reservoir which contains the waterproofing material, a rotary spider 35 having a plurality of package holders arranged in a circle concentric with the axis of rotation of the spider, said holders being open at each end to form entrance and 40 exit openings, the exit opening being lower than the entrance opening, an inclined seat for the package sloping down from the entrance to the exit end, means for rotating said spider in such manner that said package 45 holders will be caused to sweep down into the waterproofing material in the container and out of the same, a feed station from which packages are fed into one end of each holder before it enters the waterproofing 50 material and a discharge station on the opposite side of the spider at a point after the package has passed out of the waterproofing material, said discharge station being so located that the waterproofed package 55 may slide down out of the holder at said discharge station, and means for preventing the package from sliding out of the holder after it leaves the feed station until it reaches the discharge station.
- 60 4. In an apparatus for waterproofing filled packages, a container which holds a waterproofing substance, a rotary spider mounted on an inclined shaft and provided with a plurality of package holders so located that in the rotation of the spider each 65 of said package holders will successively sweep down into and out of the waterproofing material in the said container, and a conveyer adjacent said spider onto which the package is discharged from the holder at 70 some station after the holder has passed through the waterproofing material.
5. In an apparatus for waterproofing filled packages, a reservoir which contains the waterproofing substance, means for 75 heating said reservoir to keep the said waterproofing substance at a temperature above the normal atmospheric temperature, a rotary spider mounted on an inclined shaft and provided with a plurality of package 80 holders in its periphery and so located that in the rotation of the spider each of said package holders will be successively caused to sweep down into and out of the waterproofing material in said reservoir, means for retaining a package in said holder while the said spider is rotating to carry the package through the waterproofing material, a conveyer adjacent said spider onto which the package is discharged from the 85 holder at some point after the holder has passed through the waterproofing bath, and a hot chamber through which the conveyer travels with the package after it is received from the spider. 90
6. In an apparatus for waterproofing filled packages, a reservoir which contains the waterproofing material, means for heating the waterproofing material in said reservoir, a rotary spider mounted above said 100 reservoir on an inclined axis, said spider having a plurality of package holders U-shaped in cross section arranged in a circle concentric with the axis of rotation of the spider, said holders being open at each 105 end, means for rotating said spider intermittently and in such manner that during each complete rotation of the spider each one of said package holders will be caused to sweep down into the waterproofing material and out of the same, an inclined slideway located adjacent the station at which one of the said package holders stops at each interval of rest in the rotation of the spider and in such position that the 110 slideway will be in alinement with one of the open ends of said holder, a conveyer located adjacent the station of rest of each one of the holders after it has passed through the reservoir, and a hot chamber through which 115 the conveyer carries the package from the spider after it has passed through the said reservoir. 120
7. In an apparatus for waterproofing filled and sealed packages, a reservoir which 125 contains the waterproofing material, means for heating the waterproofing material in said reservoir, a rotary spider mounted above said reservoir on an inclined axis, said spider carrying a plurality of package 130

holders U-shaped in cross section and extending parallel with the axis of rotation of the spider, said holders being open at each end, means for rotating said spider intermittently and in such manner that during each complete rotation of the spider each one of said package holders will be caused to sweep down into the waterproofing material and out of the same, an inclined slideway 10 located adjacent the station at which one of the said package holders stops at each interval of rest in the rotation of the spider and in such position that the said slideway will be in alinement with one of the open 15 ends of said holders, a conveyer located ad-

jaacent the station of rest of the holder after it has passed through the reservoir, a hot chamber through which the conveyer carries the package from the spider after it has passed through the said reservoir, and means 20 for guarding the exit end of the holder during the travel from the receiving station to the discharging station.

In testimony whereof I affix my signature, in presence of two witnesses.

WILLIAM H. DOBLE.
